United States Patent Office

Des. 225,147
Patented Nov. 21, 1972

225,147

CHAIR

Morris F. Fisher, Carmel, Ind., assignor to Mohasco Industries, Inc., Amsterdam, N.Y.

Filed Jan. 4, 1971, Ser. No. 103,942

Term of patent 14 years

Int. Cl. D6—02

U.S. Cl. D6—71

FIG. 1.

FIG. 2.

FIG. 1 is a front perspective view of a chair showing my design; and

FIG. 2 is an enlarged fragmentary view showing the fabric of the side arms in greater detail.

The side of the chair not shown is like the side shown while the back is plain and unornamented.

I claim:

The ornamental design for a chair, substantially as shown and described.
